US00D364465S

United States Patent [19]

Stojanovic

[11] Patent Number: Des. 364,465

[45] Date of Patent: ** Nov. 21, 1995

[54] **DEVICE FOR ACCUMULATION,
AMPLIFICATION AND LOCAL DIRECTION
OF POSITIVE COSMIC ENERGY**

[76] Inventor: **Branislav Stojanovic**, Dragoslava Stojanovica 6, 21000 Novi Sad, Yugoslavia

[*] Notice: The portion of the term of this patent subsequent to Jan. 21, 2009, has been disclaimed.

[**] Term: 14 Years

[21] Appl. No.: 11,179

[22] Filed: Jul. 28, 1993

Related U.S. Application Data

[63] Continuation-in-part of Ser. No. 710,653, Jun. 5, 1991, abandoned.

Foreign Application Priority Data

Jun. 8, 1990 [YU] Yugoslavia 1128/90

[57] CLAIM

The ornamental design for device for accumulation, amplification and local direction of positive cosmic energy, as shown.

DESCRIPTION

FIG. 1 is a front/right side/top perspective view of a device for accumulation, amplification and local direction of positive cosmic energy showing my new design;

FIG. 2 is a front view thereof;

FIG. 3 is a top view thereof;

FIG. 4 is a rear view thereof;

FIG. 5 is a bottom view thereof;

FIG. 6 is a left side view thereof; and,

FIG. 7 is a right side exploded view thereof.
